Nelson McDonald

UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

SOFTENING MACHINE.

1,409,164.

Specification of Letters Patent. Patented Mar. 14, 1922.

Application filed May 1, 1918. Serial No. 231,946.

To all whom it may concern:

Be it known that I, FREDERICK M. FURBER, a citizen of the United States, residing at Revere, in the county of Suffolk and State 5 of Massachusetts, have invented certain Improvements in Softening Machines, of which the following description, in connection with the accompanying drawings, is a specification, like reference characters on the drawings indicating like parts in the several figures.

This invention relates to machines used for softening portions of boots and shoes preparatory to the lasting operations, and 15 in particular to that type of such machine wherein the softening agent used is steam or moist water vapor. Difficulty has been experienced with these machines in that some shoes, depending upon the kind of 20 leather, are damaged in them by "burning," which means an injury due to too long exposure to a temperature which is too high. These machines are built to hold several 25 shoes which are removed in turn (and others then substituted) and subjected to a lasting operation. It is therefore desirable that the machine be adjusted so as to treat properly a shoe in an integral multiple of the time required to perform the operation mentioned. Furthermore, in case the operator 30 has unexpected trouble with the shoe being lasted, the shoes in the softening machine remain there longer than usual. Many shoes are liable to injury from this cause, as some 35 kinds of leather, for example chrome leather, which will stand a certain temperature safely for a certain period will be badly damaged if the period be substantially increased.

In view of these and other conditions, efforts have been made to lower the temperature of the steam or vapor used in order 40 to offset an extra long period of exposure. It is a principal object of my invention to provide a softener so organized as to insure 45 that the steam or vapor used will be supplied at a temperature which will not injure the shoe materials, even if the materials for any cause are subjected to it for relatively long periods.

Saturated dry steam at atmospheric pressure has a temperature of about 212° F. It is unwise to expose leather to this temperature for a long time. It is impracticable to obtain dry saturated steam at a 50 lower temperature than this by any direct

means, as its pressure would be below atmospheric pressure. I have solved the problem by providing an apparatus that utilizes steam having a pressure greater than atmospheric pressure, that reduces the pressure at 60 a point remote from the work, and that reduces the temperature of the steam while conducting it from the point of pressure-reduction to the work through conducting means having a conducting capacity and 65 heat-reducing proportions both of which are substantially greater than those of the conduit by which the steam is conducted to the point of pressure reduction.

An important feature of the invention is 70 therefore a novel organization of shoe treating means, remote vapor controlling means, and means for conducting the vapor to the treating means and arranged to reduce the pressure and temperature of the vapor in 75 passage. In the illustrated organization, the means for conducting the vapor to the treating means provides for depriving the vapor of a substantial quantity of heat during its passage by a construction and arrangement characterized by a heat radiating surface in direct contact with the free atmosphere and of relatively great area compared to the volume of vapor and to distance traversed through the conducting means. 80

These and other features of the invention, comprising various combinations and arrangements of parts, will be understood from the following description of a preferred embodiment thereof selected for purposes of illustration and shown in the drawings in which:

Fig. 1 shows a front elevation of the apparatus; and

Fig. 2 shows a side elevation thereof. 95

The illustrated machine comprises a hollow base 10 arranged to contain water. An inlet pipe and valve 12 supply steam to the base, and an overflow pipe 14, having its mouth at a higher level than that of the 100 inlet pipe, maintains a body of water into which the entering steam is emitted, but the overflow pipe limits the accumulation of water. The steam which bubbles through the water and that which is formed from 105 the boiling water in the base will therefore be saturated or wet and may carry liquid water particles in it. Even if the pressure and temperature in the pipe 12 be above atmospheric pressure and 212° F. respectively, 110

they will be reduced to these degrees as the steam bubbles through the water in the base 10.

The shoe is held on a support 16 fastened 5 to the side of a treating chamber 18, and has its toe projecting into the chamber. The toe of the shoe rests on a wooden plate 20, to avoid damage by rust. The chamber is connected with the base by a number of 10 pipes 22 and the base and chamber are clamped on the pipes by turnbuckles 24. The pipes are made sufficiently small to have a superficial area large as compared with their internal capacity in order to facilitate 15 the escape of heat from the steam rising through them. I have found it advisable to reduce the temperature of the steam or vapor to about 140° F., and the apparatus shown has been perfectly successful 20 in achieving this result.

In the illustrated apparatus the pipes 22 were made of $\frac{1}{8}$ inch steel tubing about 22 inches long. The superficial area of the pipe per inch of length was therefore 2 25 square inches and its interior volume somewhat under 0.3 cubic inch. The superficial area was therefore large as compared with the capacity, which made the tube very efficient as a cooling agent.

30 The temperature may be regulated if desired by altering the rate of passage of the steam through the pipes. This may be done by regulating the valve 12, or by closing some of the pipes 22 by plugs or otherwise. 35 I have found, however, that it is easy to design the apparatus to produce substantially the temperature desired, and that regulation is seldom necessary.

Having described my invention, what I 40 claim as new and desire to secure by Letters Patent of the United States is:—

1. A shoe-softening apparatus comprising a treating receptacle formed to receive a pulled-over end of a shoe, a steam receptacle 45 having an inlet for steam arranged to be submerged in the water of condensation, said steam receptacle being separated from said treating receptacle, and means arranged to conduct vapor from the upper part of said steam receptacle to said treating receptacle.

2. In an apparatus of the class described, a shoe treating chamber, a receptacle for water separate from said chamber, means for conducting a heating agent into the water, and a plurality of pipes for conveying vapor from the water receptacle to the chamber, said pipes being arranged to deprive the vapor of a substantial quantity of its heat in the passage from the water receptacle to the treating chamber.

3. In an apparatus of the class described, a shoe treating chamber, a receptacle for water, means controllable by the operator for conducting a heating agent into the water, and means for conducting vapor

from the receptacle to the treating chamber, characterized by a heat radiating surface which is large as compared with the vapor-conducting capacity of said conducting means.

4. A shoe-treating apparatus comprising a water-container, a steam-pipe arranged to emit steam in a body of water in said container to saturate the steam and to vaporize the water, a shoe-treating device, and a vapor conduit exposed to the atmosphere and arranged to conduct vapor from the water container to the shoe-treating device, said means being arranged to drain the liquid of condensation back into the water-container and to dissipate excessive heat of the vapor.

5. A shoe-treating apparatus comprising a water-container, a steam-pipe arranged to emit steam in a body of water in said container to saturate the steam and to vaporize the water, a shoe-treating device separate from said water-container, and a plurality of heat-radiating conduits arranged to conduct vapor from the upper part of said water-container to the shoe-treating device and to drain the liquid of condensation away from the latter.

6. A shoe-treating apparatus comprising a water-container, a steam-pipe arranged to emit steam in a body of water in said container to saturate the steam and to vaporize the water, a shoe-treating device, and a plurality of conduits arranged to conduct vapor at substantially atmospheric pressure from the upper part of said water-container to the shoe-treating device, said conduits being exposed to the atmosphere so as to dissipate a considerable degree of heat from the vapor therein.

7. A shoe-treating apparatus comprising a water-container, a steam-pipe arranged to emit steam in a body of water in said container to saturate the steam and to vaporize the water, a shoe-treating device separate from and above said water-container, and a conduit arranged to conduct vapor from the upper part of said container to said treating device, said conduit being exposed to the atmosphere and arranged to drain water of condensation back into the water-container.

8. A shoe-treating apparatus comprising a water-container, a treating device separate from and arranged above the water-container, a plurality of pipes extending side by side from the upper part of said water-container to the treating device to support the latter and to conduct vapor from the container to the treating device, the container and the treating device having sockets into which the pipe-ends are movable by simple endwise movement, means arranged to hold the water-container, the treating device and the pipes in assembled relation,

and means for emitting a heating agent in a body of water in the container.

9. The combination with a pipe for supplying steam having a pressure exceeding atmospheric pressure and having a temperature higher than the boiling temperature, of a shoe-treating apparatus comprising a treating device, and means arranged to conduct vapor from said pipe to the treating device, said means having substantially greater conducting capacity than said pipe to reduce the pressure of the vapor to atmospheric pressure, and having relatively great heat-radiating area compared to the distance traversed by the vapor in flowing from said pipe to the treating device whereby the temperature of the vapor is reduced more rapidly while the vapor is passing therethrough than while passing through said pipe.

10. A shoe-treating apparatus comprising a treating device, vapor-conducting means connected to said device and arranged to drain the products of condensation away

from said device and to accumulate such products into a compact body, said means having an opening to receive a steam-supply pipe at a point where the steam emitted from such pipe may pass through the accumulated product of condensation before reaching the treating device.

11. A shoe-softening apparatus comprising a steam supply pipe, a steam and water receptacle connected to said pipe so as to receive steam from the latter and to wet and cool such steam with water of condensation, a pipe arranged to conduct vapor from the upper part of said receptacle, said pipe being exposed to the atmosphere and long enough to dissipate a substantial quantity of heat from the vapor flowing therethrough, and means arranged to support a shoe in position to be softened by the vapor emitted from said vapor pipe.

In testimony whereof I have signed my name to this specification.

FREDERICK M. FURBER.
